UNITED STATES PATENT OFFICE

HUGO E. GRIESHABER, OF NEW LONDON, CONNECTICUT, ASSIGNOR TO ELECTRIC BOAT COMPANY, OF GROTON, CONNECTICUT, A CORPORATION OF NEW JERSEY

MINE-LAYING SUBMARINE BOAT

Application filed December 24, 1926. Serial No. 156,898.

My invention relates to the laying of mines in warfare and has particular reference to the laying of mines from submarine boats.

My invention contemplates the discharge of mines from the waist of the ship through the bottom thereof, the mines being stowed in a midship compartment in proximity to one or more properly located expulsion tubes.

My invention is illustrated, more or less schematically in the accompanying drawings, in which,

Figure 1 is a longitudinal sectional view of the midship portion of the craft, and

Figure 2 is a transverse sectional view taken on the plane of the line 2—2 of Figure 1.

The outer hull of the submarine boat is illustrated at 3, and the inner hull thereof at 4. Forwardly in the admidships compartment 5, racks 6, 6 are located for the stowing of mines *m*, *m*, as shown and a plurality of expulsion tubes 7, 7 are mounted within the compartment in proximity to the racks, these tubes extending through the bottom and being inclined aft as illustrated.

Each of the tubes 7 is provided with a lower or outer cover 8 and an upper or inner cover 9, both operable from within the compartment in a manner to be pointed out presently, and a compensating tank 10, located abreast of racks 6, is connected with each of the tubes 7 by suitably valved piping 11, as indicated. The mines are introduced into the compartment by way of the hatch 12.

Normally, lower covers 8 are closed and upper covers 9 are open, the tubes being cleared of water. The mines *m* are moved aft in the racks and loaded into the tubes, upper covers 9 being then securely closed and the free space in the tubes flooded with water from the compensating tank 10.

When a mine is to be layed, the lower cover of a tube is opened, the mine either dropping out by gravity or being discharged by compressed air led to the tube from a suitable source. After dropping or discharging the mine the lower cover is again closed, with the tube, of course, completely full of water, and this water is then blown from the tube to the tank, thus compensating for the lost weight

and clearing the tube for the reception of another mine as above described.

I claim:

1. In a submarine boat, a midship compartment, a mine expulsion tube mounted in said compartment, inclined aft, and discharging through the hull bottom, inner and outer covers for said tube, and a compensating tank having valved connection with said tube. 55

2. In a submarine boat, a midship compartment, a mine-stowing rack mounted forwardly therein, a mine expulsion tube mounted in said compartment in proximity to and aft of said rack, said tube being inclined aft and discharging through the hull bottom, inner 65 and outer covers for said tube, and a compensating tank mounted abreast of said racks and having valved connection with said tube.

3. In a submarine boat, a midship compartment, a mine-stowing rack mounted forwardly therein, a mine expulsion tube mounted in said compartment in proximity to and aft of said rack, said tube being inclined aft and discharging through the hull bottom, inner and outer covers for said tube, a compensating tank mounted abreast of said racks, 70 and having valved connection with said tube, 75 and a hatch through the hull top.

4. In a submarine boat, a plurality of mine expulsion tubes opening through the bottom thereof, closures for the ends of the tubes, and racks disposed above and in proximity to and aligned with the respective tubes and adapted to each support a plurality of mines in position to be readily loaded into 80 the tubes. 85

5. In a submarine boat, a plurality of mine expulsion tubes opening through the bottom thereof, closures for the ends of the tubes, and racks disposed above and in proximity 90 to the upper ends of the tubes, the racks being substantially in the planes of the respective tubes and adapted to each support a plurality of mines in superposed relation. 95

6. In a submarine boat, a plurality of mine expulsion tubes opening through the bottom thereof, closures for the ends of the tubes, and racks disposed above and in proximity to the upper ends of the tubes, the racks being substantially in the planes of the re- 100

spective tubes and adapted to each support a plurality of mines in superposed relation and in position to be inserted into the tubes by a simple endwise motion.

5 7. In a submarine boat, a mine expulsion tube opening through the bottom thereof and inclined aft, closures for the tube, and a vertical rack in proximity to the upper end of the tube and substantially in the plane thereof, said rack being adapted for supporting a plurality of mines in superposed relation.

10 8. In a submarine boat, a midship compartment, a mine expulsion tube mounted in said compartment and discharging through the hull bottom, closures for the tube, and a rack in proximity to the upper end of the tube and in substantially the plane thereof, said rack being adapted to support a plurality of mines in superposed relation and 15 in position to be inserted into the tube.

20 9. In a submarine boat, a plurality of mine expulsion tubes discharging through the bottom thereof and disposed in alignment transversely of the hull, closures for the ends of the tubes, and a series of racks in substantially the planes of the respective tubes and in proximity to the upper ends thereof, said racks being each adapted to support a plurality of mines in superposed relation and in 25 position to be inserted into the tubes by a simple endwise movement.

30 10. In a submarine boat, a midship compartment, a plurality of mine expulsion tubes in said compartment and discharging through the hull bottom, closures for the ends of the tubes, and a series of racks in said compartment and in proximity to the upper ends of the tubes, said racks being disposed substantially in the planes of the respective tubes and being adapted to each support a plurality of mines in superposed relation and endwise to the tubes.

35 11. In a submarine boat, a midship compartment, a plurality of mine explosion tubes in said compartment, said tubes being inclined aft and discharging through the hull bottom, closures for the ends of the tubes, and a plurality of racks in the compartment in proximity to the upper ends of the tubes 40 and in substantially the planes of the respective tubes, said racks being adapted to each support a plurality of mines in superposed relation and endwise to the tubes.

45 12. In a submarine boat, a mine expulsion tube opening through the bottom thereof, closures for the ends of the tube, and a rack disposed in proximity to and aligned with the tube and adapted to support a plurality of mines in endwise relation to the tube in position to be readily loaded from the rack directly into said tube.

50 13. In a submarine boat, a mine expulsion tube opening through the bottom thereof and inclined aft, closures for the ends of the tube, and a rack disposed forwardly of the tube in

55 proximity thereto, said rack being aligned with the tube and adapted to support a plurality of mines in endwise relation to the tube in position to be readily loaded into said tube from the rack.

60 14. In a submarine boat, a mine expulsion tube opening through the bottom thereof, and inclined aft, closures for the ends of the tube, and a rack disposed forwardly of the tube in proximity thereto, said rack being aligned with the tube and adapted to support a plurality of mines in position to be loaded into said tube.

65 In witness whereof, I hereunder subscribe my name this 20th day of December, 1926.

HUGO E. GRIESHABER.
